2 SHEETS—SHEET 2.

UNITED STATES PATENT OFFICE.

ARMAND H. PEYCKE, OF CHICAGO, ILLINOIS, ASSIGNOR TO AMERICAN STEEL FOUNDRIES, OF NEW YORK, N. Y., A CORPORATION OF NEW JERSEY.

SPRING-DAMPENER.

1,169,862.

Specification of Letters Patent.

Patented Feb. 1, 1916.

Application filed July 30, 1915. Serial No. 42,692.

To all whom it may concern:

Be it known that I, ARMAND H. PEYCKE, a citizen of the United States, and resident of Chicago, in the county of Cook and State 5 of Illinois, have invented certain new and useful Improvements in Spring-Dampeners, of which the following is a specification.

My invention relates to shock absorbing devices and has particular reference to a 10 novel spring dampener adapted for use in connection with the nest of springs commonly employed in car trucks.

A series of extensive tests have developed the fact that the springs which serve to 15 silently support the bodies of railway cars act in a peculiar manner. For instance, it was found that the inequalities of the track or roadbed caused a slight compression of the springs carried by the car truck and 20 that under certain conditions the deflections were cumulative; that is, the car body had a tendency to teeter, the up and down movement under the action of the springs increasing progressively until the point was 25 reached at which the springs were completely compressed and the vibration of the car body stopped thereby. Very shortly thereafter the same action was found to be repeated. This action, of course, is deleterious, not only to the springs but to the road bed and the car. The ordinary vibrations of the car would not be serious but the shock of the full compression of the springs is transmitted throughout the structure of the 35 car and to the roadbed. This has been sought to be overcome by the use of greater capacity springs with the result that the required resiliency under light shocks is not present. It has been found therefore that 40 the vibration or teetering of the car may be eliminated without material loss in the resiliency of the springs by the provision of a dampener or friction element in connection with each nest of springs.

My invention therefore has for its object 45 the provision of novel means adapted for association with a nest of springs whereby the cumulative vibration of the car is eliminated.

A further object is to provide means which 50 may be of a size sufficient to permit their location at the center of a nest of four springs such as are commonly employed in freight car trucks.

The invention will be more readily under-

stood by reference to the accompanying drawings, wherein,

Figure 1 is a sectional elevation through a nest of springs to which my novel dampener has been applied; Fig. 2 is a similar view taken at right angles to Fig. 1; Fig. 3 is a section on the line 3—3 of Fig. 1; Fig. 4 is a vertical section through a slightly modified form; Fig. 5 is a section on the line 5—5 of Fig. 4; Fig. 6 is a vertical section through a further modification, and Fig. 7 is a section on the line 7—7 of Fig. 6.

Referring more particularly to the drawings and to Figs. 1 to 3 inclusive in detail, it will be seen that I provide my spring 70 dampener, at a point substantially in the middle of a nest of four springs 10. It is common practice to arrange the springs as shown between upper and lower spring plates 11, 12, and to place the springs in the 75 car truck in this manner. The arrangement serves to facilitate handling and shipping and maintains the springs in their proper location and alinement when in the car truck. The upper and lower plates are 80 commonly connected by suitable means permitting compression of the springs.

In the construction shown in Figs. 1 to 3, I have employed the common form of upper and lower plates or caps and at the axial 85 center of the upper plate I attach a squared barrel 13, which projects downwardly to a point near the lower plate 12. The barrel is rigidly secured to the upper spring cap by means of an inturned flange 14. Secured to 90 the lower spring plate 12, is a button or flanged projection 15, which may be riveted in place. Mounted within the barrel 13, are counterpart castings, each provided on its lower end with a flange 16, which underlies 95 the flange 17, on the button 15. Above the flange 16, of the castings, is a floor or ledge 18, which acts as a seat for a coiled spring 19, the upper end of which engages a cone 20, lying between the conical surfaces 21, 100 formed on the counterpart castings. The spring 19, is inserted under compression and the tendency thereof is to force the cone 20, upward and to spread the counterpart castings. This spreading tendency is resisted by 105 the barrel 13, and frictional resistance is interposed against the vertical reciprocation of the plates 11, 12, under the action of the large springs 10.

As best shown in Figs. 1 and 2, I provide 110

for limited bodily vertical movement of the lower spring plate 12, with relation to the counterpart castings; that is, the large springs 10, are adapted for a limited reciprocation without the interposition of the frictional resistance provided. This result is secured by providing the space 22, above the button, and a similar space 23, between the ends of the counterpart castings and the lower plate 12. This provides for the free action of the springs under light shocks.

In the construction shown in Figs. 4 and 5, the top and bottom caps 24, 25, respectively are each provided with a tubular extension 26 and 27, rectangular in cross section, which is secured to the axis of the plate and is located at the center of a group of four springs. Projecting into each of the tubular extensions 26, 27, are castings 28, 29, which are duplicates and which tightly engage the inside walls of the tubular portions 26, 27. The castings 28, 29, at their ends, are of increased thickness, providing a conical recess 30, therebetween, within which recess 30, are mounted conical blocks 31, 32, in opposed relation and urged apart by a coil spring 33. The block 31 is centered with relation to the cap plate 24, by a bolt 34, the head of which is countersunk in the plate 24. It will be noted that the spring tends to force the conical wedges against the conical surfaces of the members 28, 29, and to force these members tightly against the walls of the tubular extensions, thereby securing the frictional resistance necessary.

In the construction of Figs. 6 and 7, the plates 35, 36, are similar to those heretofore described. To the plate 35, is secured a rectangular tube 37, within which a similar rectangular tube 38, secured to the lower plate, is placed. The tube 38, is provided with a portion of increased cross sectional area, thereby forming conical recesses 39, 40. Mounted in the recess 39, is the head 41, of the bolt 42, the lower end of which bolt engages a nut 43, a flange of which serves as a seat for a coiled spring 44. The upper end of the spring engages a conical block 45, mounted in the recess 40. Inasmuch as the

tubular portion 38, is split or divided on a vertical line, as indicated in Fig. 7, the conical blocks 41, 42, tend to force the two halves of the member 38 against the inside surfaces of the rectangular tube 37, and to thereby produce the required frictional resistance for relative movement of the plates 35, 36, with the car springs associated therewith.

I have illustrated a number of modifications in this and my copending application, Serial No. 42,693. Such other modifications as are within the scope of my claims I consider within the spirit of my invention.

I claim:

1. In a device of the class described, the combination of a spring, a plate mounted at each end of said spring, each of said plates being provided with a tubular projection at the center of the plate, and friction inducing means acting upon said tubular projections, said last named means including a spring advanced wedge, substantially as described.

2. In a device of the class described, the combination of a plurality of springs, a spring cap at each end of said springs, an incompressible tubular projection from one of said caps, a split tube secured to the other of said caps and a spring advanced wedge acting upon said split tube and tending to force the same against the inner walls of said incompressible tube, substantially as described.

3. In a device of the class described, the combination of a nest of springs, a spring cap for each end of the spring, an incompressible tubular projection from the center of one of said caps, a split tube secured, but permitted limited relative longitudinal movement with relation to the other cap, a wedge located interiorly of said split tube, and a spring acting upon said wedge, substantially as described.

Signed at Chicago, Ill., this 27th day of July, 1915.

ARMAND H. PEYCKE.
